GRAIN CAR DOOR STRUCTURE

Michael J. Ford, Hartsdale, N.Y., assignor, by mesne assignments, of one-half to International Paper Company, New York, N.Y., a corporation of New York, and one-half to The Stanley Works, New Britain, Conn., a corporation of Connecticut

Filed Mar. 16, 1959, Ser. No. 799,683
5 Claims. (Cl. 160—114)

This invention relates to a grain door and support method. The invention is useful in connection with closures for door openings, oppositely-disposed door openings in boxcars, and for various other openings for which a seal is needed. The invention will be described herein in connection with a railway boxcar.

An object of the invention is to provide an improved grain door structure which is highly effective in containing granular material while at the same time providing a structure that can be readily folded for shipment and readily installed within the car. A further object is to provide a structure in which the heavy pressures encountered in the hauling of grain and other heavy material are effectively resisted and the pressure directed to areas where it is utilized in holding the grain closure in position. A still further object is to provide a grain door structure of unique form and of great strength providing greater flexibility and ease of installation. A still further object is to provide a combination of doors with interconnecting means having the advantages which will be hereinafter described in detail. Other specific objects and advantages will appear as the specification proceeds.

The invention is shown, in an illustrative embodiment, by the accompanying drawing, in which—

FIGURE 1 is a broken perspective view of a railway car equipped with openings closed by doors and support means embodying my invention; FIG. 2, a broken top plan view; FIG. 3, a detail sectional view, the section being taken as indicated at line 3—3 of FIG. 1; FIG. 4, a broken perspective view of the door in folded relation; and FIG. 5, an enlarged detail sectional view of a portion of the door body showing the laminated structure employed.

In the illustration given, A designates a railway car provided with opposite door openings enclosed by frames A'.

Secured to each frame A' is a door body 10 having the side edges thereof folded upon itself at 11 and secured to the door frame by nails extending through the batten 12. It will be understood that any suitable means for securing the edges of the door body 10 may be employed.

Each door 10 is provided at its center with a U-shaped portion 13 enclosing a metal bar 14 and secured thereto by strong adhesive 15. The door body 10 is preferably provided with a fold line 16 at the outer end of each bar so that the side panels 10a may be turned outwardly at an inclination toward the frame members A' and secured thereto. The bar 14 is provided with an opening 17 therethrough adapted to receive the tension wires 18, and the door portion 13 is provided also with an opening 19 therethrough aligned with the bar opening 17.

I prefer to equip the panels 10a each with a floor flap 20 so as to provide a seal along the bottom of each door panel. As shown more clearly in FIG. 2, the inclined side panels 10a form a V-shaped recess on the outer side of the panels, and similarly the floor flaps 20 provide between them a V-shaped opening. A cover flaps 21 is provided to cover the area between the floor flaps 20 so that there is a continuous flap seal around the door body 10 and on which the grain rests as a means for further holding the door compactly against the floor.

The tension wires 18 are drawn inwardly to hold the

2

bars 14 inwardly of the door frame A' so that the side panels 10a of each door slope outwardly toward the door frame A'. With this arrangement, it is found that the grain pressure at the center of the car is reduced and the pressure increased adjacent the frame portions A' so as to aid in further anchoring the door sides against the frame. The arrangement further protects the storm doors of the railway car so that they cannot contact at any time the door body 10 and rub against it during transit and during the starting and stopping of the car. The structure further enables a pry-board to be placed on the outside of the door 10 and against the door frame, if this is desired. Yet another advantage is that the central bar 14 provides a vertical support enabling the workman to leave the car after the installation is completed.

I have found that a highly effective door body 10 can be provided by employing laminated liner paper such as kraft paper, with the paper plies bonded together with adhesive, the plies being illustrated in FIG. 5. The number of plies may be varied widely depending upon the type of paper employed and the loads that will be supported by the door. Plastic adhesives may be employed for securing the paper plies together and to further strengthen the paper. In the illustration given in FIG. 5, there are three sheets 22 which are bonded together, but, as stated, the number of plies may be varied.

As illustrated best in FIG. 4, the door can be conveniently folded upon itself into a compact shipping package and the folded structure further assists the operator in the actual installation, since the V-shaped position of the panels 10a supports the structure in upright position while the operator is nailing the sides to the door frame A'.

The cover flap 21, which bridges the space between the floor flaps 20, may be a separate piece, or it may be secured to one of the flaps 20 with a fold line which permits it to be turned upon itself.

While I have described the structure 10 as being formed of laminated liner or paper sheets bonded together to provide the desired strength and flexibility, it will be understood that other material may be employed, including paper provided with reinforcing fibers running in opposite or angularly-related directions, or the structure may include laminations of plastic sheets with paper sheets or other fiber sheets to provide the desired strength. Corrugated paper may also be employed. Further, the door body 10 may be employed alone or in combination with steel straps or other supporting straps, as illustrated in U.S. Patents No. 2,734,567 and 2,797,749. If steel reinforcing is employed, the steel straps may be extended through a projected portion of the metal bar 14. One advantage, however, of the structure herein described is that the reinforcements can be to a substantial degree omitted because of the angular arrangement of the door and the supporting means therefor.

While, in the foregoing specification, I have shown a specific structure in considerable detail for the purpose of illustrating an embodiment of the invention, it will be understood that such details may be varied widely by those skilled in the art without departing from the spirit of my invention.

I claim:

1. In combination with a freight vehicle having opposite door openings enclosed by frames, a door across each opening having a central bar and door portions inclined outwardly therefrom, means for anchoring the sides of said portions to said frames, each of said doors being equipped with a central pocket enclosing its associated bar, an opening in each bar and a pair of openings in the associated central pocket aligned with said bar openings, and tension means extending through the openings of said doors to draw said doors inwardly, whereby said door

panels form a V recess with the panels inclined from the center of the door outwardly to said door frames.

2. In combination with a freight vehicle having opposite door openings enclosed by frames, a door closure across each opening having a central, vertically-extending, elongated bar and door portions inclined outwardly therefrom, said bar having a generally rectangular transverse section, means for anchoring the sides of said door portions to said frames, each closure being equipped with a central, vertically-elongated pocket portion about its associated bar, a plurality of openings extending through said bars generally parallel with said doorway, a pair of openings in said pocket portion for each bar opening and aligned therewith, and tension means extending between the opposite enclosure openings maintaining each closure in a V configuration.

3. In combination with a freight vehicle having opposite door openings enclosed by frames, a vertically-extending, generally rectangular door closure across each opening, means for anchoring the vertical sides of said closures to said frames, said closure comprising a panel folded on itself centrally along a plurality of spaced-apart, parallel fold lines to develop an integral U-shaped part extending inwardly of said vehicle, means uniting the panel portions between fold lines in immobilized relation relative to each other to maintain said part in a U shape, said U-shaped part being equipped with reinforcing means, aligned tie-wire-receiving openings in said parts and reinforcing means, and tie-wire means interconnecting the U-shaped parts of the oppositely-disposed closures.

4. In a method of closing grain car doors, the steps of folding a generally rectangular, planar paperboard panel along a plurality of centrally-disposed, spaced-apart, parallel fold lines to develop a centrally disposed, U-shaped portion outstandable from the remainder of said panel when said panel is disposed in generally planar condition, uniting panel portions between said fold lines in immobilized relation relative to each other to maintain said portion in U shape, folding said panel on itself to form a generally V configuration, with said U-shaped portion at

10 the apex of said V configuration to provide a reduced sized panel for shipment, subsequently unfolding said V configuration, and securing opposite sides of said panel to the door posts of a grain car with said U-shaped portion 15 facing the interior of the car.

5. In combination with a freight vehicle having a door opening defined by vertical framing members and a floor, a temporary door extending across said opening and comprising a planar panel of generally rectangular configuration and having two pairs of opposite side edges, said panel being centrally folded on itself along a plurality of spaced-apart, parallel fold lines to provide an integral U-shaped part outstandng from the remainder of said panel and said member, when said panel is disposed in generally planar condition and secured across said opening, means uniting the panel portions between fold lines in immobilized relation to each other to maintain said part in U shape, said U-shaped part being equipped with reinforcing means, a portion of said panel adjacent only one side edge of one pair of side edges being equipped with a fold line outstanding and being positioned against said floor to provide a seal against the escape of lading in said vehicle, and means securing the other pair of side edges to said members, said panel being adapted to be folded on itself to form a generally planar reduced size shipment package with said U-shaped part at the apex of said fold.
